PHOTOELECTRIC DEVICE FOR DISTRIBUTING
STRANDS ON A REEL

Luther K. Schneider, Timonium, Md., assignor to Western Electric Company, Incorporated, New York, N.Y., a corporation of New York

Filed Apr. 2, 1964, Ser. No. 356,759
4 Claims. (Cl. 250—222)

This invention relates to a device for properly distributing a strand on a take-up reel and particularly to a device for photoelectrically controlling the spacing between convolutions of a strand on a reel.

In the manufacture of strands such as electrical cable, it is necessary to take the strand up on a reel preparatory to subsequent stranding operations or shipment. It is essential that the strand be properly distributed on the reel so that it can subsequently be pulled from the reel without damage to or snagging of the strand.

If the spacing between convolutions of a strand on a reel is too wide, subsequent layers of the strand on the reel will fall down between the convolutions. Thus, the strand will become caught on the reel restricting its subsequent removal. If the spacing between convolutions of the strand on a reel are too close, the strand will rub against adjacent convolutions as it is taken up on and payed off of the reel causing damage to the strand. It is, therefore, highly desirable to properly distribute a strand on a reel so as to facilitate its removal without damage to the strand.

Additionally, while strand distributors are available in the prior art which will properly distribute a strand of a given diameter on a reel of a given size when rotated at a given speed, the instant invention distributes a strand on a reel independently of such parameters.

It is, therefore, an object of this invention to control the distribution of a strand on a reel so as to maintain a predetermined spacing between the convolutions.

Another object of the invention is to sense the distance between a strand and its adjacent convolution for controlling a distributor traversing a reel so as to maintain a predetermined spacing between the convolutions on a reel.

With these and other objects in view, the instant invention contemplates the utilization of a strand follower which is positioned between a strand and its adjacent convolution, the strand follower supporting a photoelectric sensing device for sensing the spacing between the strand and the adjacent convolution, the photoelectric sensing device controlling, in response to the spacing between the strand and the adjacent convolution, the rate at which a strand distributor traverses a reel so as to maintain a predetermined spacing between the strand and its adjacent convolution.

A more complete understanding of the objects and advantages of the instant invention may be obtained in the following detailed description, in which:

FIG. 1 is a partially broken away side view of a take-up reel mechanism utilizing the principles of the instant invention;

FIG. 2 is a sectional view of FIG. 1 taken along the lines 2—2 thereof;

FIG. 3 is a sectional view of FIG. 1 taken along the lines 3—3 thereof;

2

FIG. 4 is a sectional view of FIG. 2 taken along the lines 4—4, and

FIG. 5 is an electrical schematic showing a control circuit for the apparatus illustrated in FIG. 1.

In FIG. 1 a strand follower is generally indicated by the numeral 10. The strand follower 10 is positioned between successive sections of a portion of a strand 11 and an adjacent convolution 12 of the strand 11 wound on a reel, indicated generally by the numeral 14. A distributor 13 traverses the reel 14 to distribute the strand 11 on the reel. The strand follower 10 is mounted on a horizontal support 15 for free vertical displacement on guides 16—16. The horizontal support 15 is mounted on parallel rails 17—17 by bearings 18—18 so as to permit free displacement of the horizontal support 15 parallel to the longitudinal axis of the reel 14 in response to movement of the strand follower 10.

A solenoid 19 actuates a plunger 20 for lifting the strand follower 10 on the vertical guides 16—16. When 20 the solenoid 19 is de-energized, the strand follower 10 will drop freely on the guides 16—16 to the reel 14. As seen in FIG. 2, the strand follower 10 is provided with a plurality of cylindrical bearings 21—21 which support the strand follower 10 on the convolution 12 of the strand 11.

The distributor 13 is displaced relative to the reel 14 by a traversing screw 25. The direction in which the traversing screw 25 is rotated controls the direction which the distributor 13 is displaced relative to the reel and the speed at which the traversing screw 25 is rotated controls the speed at which the distributor 13 is displaced relative to the reel. The traversing screw 25 is positioned generally parallel to the longitudinal axis of the reel 14 so as to displace the distributor 13 generally parallel to the longitudinal axis of the reel 14 as the traversing screw 25 is rotated. A distributor motor 26 is a reversible motor whose direction and speed can be controlled as disclosed infra to rotate the traversing screw 25 in the desired direction and at the desired speed to displace the distributor 13 relative to the reel 14.

In FIG. 3, wheels 27—27 are shown in positions between the last convolution 12 of the strand wound on the reel 14 and the portion of the strand 11 approaching the reel 14. As the reel 14 turns, the wheels 27—27 will ride between the approaching portion of the strand 11 and convolution 12 of the strand 11 and is supported on the convolution 12 of the strand 11 by the bearings 21—21 to advance the strand follower 10 with the strand 11.

In FIG. 4, the wheel 27 is disclosed as being mounted in a housing 28 and spring biased downwardly by a spring 29. As the effective winding diameter of the reel 14 increases as additional layers of the strand 11 are placed on the reel, the wheels 27—27 are permitted vertical displacement in the housing 28 by the spring 29 to compensate for such increase in outside diameter.

A photoelectric cell 30 is responsive to light from a light source 31 and the amount of light striking the photocell 30 is determined by the spacing between the convolution 12 and strand 11.

As seen in FIG. 5, as light from light source 31 strikes a photocell 30, a current will be induced to increase the negative bias of a grid 32 which, in turn, will inhibit the current flow through a vacuum tube 33. As the current flow through the vacuum tube 33 is decreased, the current to the motor 26 is reduced thus reducing the speed of the distributor motor 26. Conversely, as the light from the

ht source 31 decreases, current flow through the photocell 30 also decreases decreasing in turn the negative bias on the grid 32. This permits a greater current flow through the vacuum tube 33 to increase the current flow in the motor 26 and increase the speed of the distributor motor 26. When no light strikes the photocell 30, no current will flow to the grid 32 and the maximum current flow in the motor 26 will be obtained.

By adjusting a rheostat 35, a desired bias on the grid 32 can be obtained for a given spacing between the approaching section of the strand 11 and its adjacent convolution 12. As the bias on the grid 32 determines the speed of the distributor motor 26 for a given spacing between the approaching portion of the strand 11 and its adjacent convolution 12, the proper speed for the distributor motor 13 to maintain this given spacing can be selected by adjusting the rheostat 35.

As seen in FIG. 2, as the predetermined spacing between the convolution 12 and the strand 11 is exceeded, it is necessary to decrease the speed of distributor 13 to compensate therefor. On the other hand, if the spacing between the convolution 12 and the strand 11 is less than the predetermined spacing, it is necessary to increase the speed of the distributor 13 to compensate therefor. As discussed supra, the spacing between the strand 11 and the convolution 12 determines the amount of light which strikes the photocell 30. Therefore, the speed of the distributor motor 26 is decreased when the spacing between the strand 11 and its adjacent convolution tends to exceed predetermined distance and the speed of the distributor motor 26 is increased when the spacing between the strand 11 and its adjacent convolution tends to be less than a predetermined distance.

As shown in FIG. 5, current is directed to the distributor motor 26, the light source 31, the photocell 30 and the vacuum tube 33. As a switch 41 is normally closed, the vacuum tube 33 receives current and transmits current to the distributor motor 26. The amount of light reaching the photocell 30 from the light source 31 is determined by the spacing between the strand 11 and the adjacent convolution 12 and controls the speed of the distributor motor 26 by varying the current to the motor.

A switch 42 controls the direction of rotation of the motor 26 and, thus, the direction the distributor 13 is displaced by reversing the direction of the current flow to coil 34 in the field of the motor 26. The switch 42 is controlled by a solenoid 43 and the solenoid 43 is energized and de-energized by a switch 44. As shown, the solenoid 43 is de-energized when the switch 44 is open and energized when the switch 44 is closed. When the solenoid 43 is de-energized, the switch 42 assumes the position shown in FIG. 5; and when the solenoid 43 is energized, the switch 42 is displaced to reverse the direction the current flows through the coil 34.

If, for example, the switch 44 is open as shown in FIG. 5 and the distributor 13 is displaced towards the viewer in FIG. 1, when the strand follower 10 reaches the end of its travel, a switch actuator 45 strikes a rim 46 of the reel 14 to close the switch 44 and actuate the solenoid 43 to reverse the distributor motor 26. The switch 44 remains closed until the strand follower reaches the opposite end of the reel 14 and the switch actuator 45 strikes the opposite rim, rim 47, of the reel to open the switch 44 and actuate solenoid 43 to reverse the motor 26 to its original direction. The switch actuator 45 may be made of any length necessary to reverse the motor 26 at the proper time.

As the strand follower reaches the rim 46 and the switch actuator 45 is actuated, a switch actuator 48 also strikes the rim 46 to close a switch 49. The switch 49 remains closed only as long as the switch actuator 48 is actuated. The switch 49 directs current to a solenoid 50 to energize the solenoid to close switches 55 and 56 and to open switch

55. Switch 55 when closed continues to direct current to solenoid 50 so that upon contact switch 49 being opened, switch 55 will lock solenoid 50 to hold switches 55 and 56 closed and switch 41 open. Switch 55 also directs current to the solenoid 19 to lift the strand follower 10 on the guides 16-16.

The switch 56 directs current to a magnetic counter 57. The rim 46 is provided with a plurality of spaced magnets 58-58. As the reel 14 rotates, the magnetic counter 57 counts the magnets 58-58 as they pass by, and after a predetermined number of counts, energizes a solenoid 59 to close a switch 60. Upon the switch 60 being closed, current is directed to the motor 26 to start the distributor 13 moving relative to the reel 14. A rheostat 61 is preset to provide the proper current to the motor 26 so that the distributor 13 will be displaced at the proper speed relative to the reel 14.

As the switch 41 is opened, the vacuum tube 33 is out of the circuit and is not responsive to the photocell 30 to control the speed of the distributor 13. Thus, until the switch 60 is closed, the distributor 13 remains stationary relative to the reel 14. This provides the dwell period necessary for the strand 11 to be laid substantially one full turn against the rim of the reel before the distributor starts back across the reel. By varying the number of counts necessary to actuate the solenoid 59, any desired dwell period may be obtained.

Also, after a predetermined number of counts, the magnetic counter 57 actuates a solenoid 62 to open a switch 63. The switch 63 cuts off the current to the solenoid 50 thereby opening the switches 55 and 56 and closing the switch 41. As the switch 56 opens, the counter 57 is de-energized and reset, opening the switch 60 and closing the switch 63. Solenoid 19 is also de-energized to permit the strand follower 10 to drop on guides 16. The strand follower 10 is lifted so as to permit the strand 11 to move a sufficient distance from the rim 46 so that when the strand follower is dropped, it will be placed between the strand 11 and its adjacent convolution. The number of counts at which the magnetic counter will actuate the solenoid 62 is selected so as to properly drop the strand follower between the strand 11 and its adjacent convolution 12.

As the strand follower 10 travels across the reel to the opposite rim 47, a switch actuator (not shown) which is identical to and directly opposite switch actuator 48, strikes the rim 47 to actuate contact switch 64 thereby directing current to solenoid 50 so as to repeat the sequence described supra.

In operation

55. When the distributor 13 is moving towards the viewer in FIG. 1, the speed of the distributor is controlled by the photocell 30. As the distributor 13 reaches the end of the reel 14, switch actuators 45 and 48 close switches 44 and 49, respectively. Switch 44 reverses the motor 26 and switch 49 energizes solenoid 50 to close switches 55 and 56 and open switch 41. This stops the displacement of the distributor and lifts the strand follower 10.

After a predetermined dwell interval, the solenoid 59 is energized by the magnetic counter 57 to close the switch 60 and start the distributor 13 back across the reel 14. After a predetermined interval, the solenoid 62 is actuated by the magnetic counter 57 to open the switch 63 and de-energize the solenoid 50. This opens switches 55, 56 and 60 and closes switches 41 and 63 to drop the strand follower 10, reset the counter 57 and return the control of the speed of the strand distributor 13 to the photocell 30.

When the strand follower 10 reaches the end of its travel in the opposite direction, the switch actuator 45 strikes the rim 47 to open the switch 44 and reverse the

direction of the motor 26 to its original direction. An actuator (not shown) also strikes the rim 47 to close the switch 64 so as to energize solenoid 50. Solenoid 50 closes switches 55 and 56 and opens switch 41. This lifts the strand follower 10, energizes the counter 57 and stops the movement of the distributor 13.

After a predetermined dwell interval, the solenoid 59 is actuated by the counter 57 to start the distributor 13 moving in the opposite direction across the reel 14. After a second predetermined interval, the solenoid 62 is actuated by the counter 57 to open switch 63 thereby de-energizing the solenoid 50 to open the switches 55, 56 and 60 and to close the switches 41 and 63. This drops the strand guide 10, de-energizes the counter 57 and returns the control of the speed of the distributor 13 to the photocell 30.

Any suitable, conventional arrangement may be used to support the rails 17 relative to the reel 14 so as to support the horizontal support 15. Further, any conventional facility may be utilized for rotating the reel 14 about its longitudinal axis. Preferably, a conventional torque motor is utilized to rotate the reel in order to maintain a constant tension in the strand 11. In the same manner, the motor 26 and traversing screw 25 may be mounted by any conventional arrangement.

It is to be understood that the above-described arrangement of apparatus and construction of elemental parts is simply illustrative of an application of the principles of the invention and many other modifications may be made without departing from the invention.

What is claimed is:

1. A device for distributing a strand on a reel, comprising:

a strand distributor mounted for reciprocal movement transverse to the reel,

means for displacing the strand distributor,

a light source mounted substantially independently of the strand distributor on one side of the reel for free displacement transverse to the reel with a strand when the strand is distributed on the reel,

a photoelectric sensing element mounted on the opposite side of the reel for free displacement with the light source for receiving light from the light source, the amount of light reaching the photoelectric sensing element from the light source being a function of the distance between the strand and its adjacent convolution, and

means responsive to the amount of light reaching the photoelectric sensing device for controlling the rate at which the strand distributor traverses the reel.

2. A device for distributing a strand on a reel, comprising:

a strand distributor mounted for reciprocal movement transverse to the reel,

means for displacing the strand distributor,

a light source mounted substantially independently of the strand distributor on one side of the reel for free displacement transverse to the reel with a strand when the strand is distributed on the reel, the light from the light source being directed substantially tangentially of the effective winding surface of the reel and between the last convolution of strand wound on the reel and section of the strand approaching the reel,

a photoelectric sensing element mounted on the side of the reel opposite to the light source for free displacement with the light source, the amount of light reaching the photoelectric sensing element from the light source being a function of the distance between the strand and its adjacent convolution, and

means responsive to the amount of light reaching the photoelectric sensing device for controlling the rate at which the strand distributor traverses the reel.

3. A device for distributing a strand on a reel, comprising:

a strand distributor mounted for reciprocal movement transverse to the reel,

means for displacing the strand distributor,

a carriage mounted for free displacement vertically of and transverse to the reel with a strand when the strand is distributed on the reel, the carriage having strand follower means depending therefrom which ride between the last convolution wound on the reel and the portion of the strand approaching the reel and cause movement of the carriage substantially parallel to the axis of the reel,

a light source mounted on the carriage substantially independently of the strand distributor and carried by the carriage on one side of the reel, the light from the light source being directed substantially tangentially of the effective winding surface of the reel and between the last convolution of strand wound on the reel and section of the strand approaching the reel, a photoelectric sensing element mounted on the carriage directly opposite the light source and on the side of the reel opposite to the light source, the amount of light reaching the photoelectric sensing element from the light source being a function of the distance between the strand and its adjacent convolution,

means responsive to the amount of light reaching the photoelectric sensing device for controlling the rate at which the strand distributor traverses the reel,

means actuated upon the carriage reaching either end of the reel for lifting the carriage,

means actuated upon the strand reaching either end of the reel for stopping the displacement of the distributor and for reversing the distributor at each end of the reel, and

means for lowering the carriage after the distributor has moved a predetermined distance from either end of the reel to permit the section of strand approaching the reel to move to the other side of the strand follower means depending from the carriage.

4. A device for distributing a strand on a reel, comprising:

a reel mounted for rotation about its longitudinal axis and having a plurality of magnetized portions spaced at equal intervals about one flange,

a strand distributor mounted for reciprocal movement transverse to the reel,

means for displacing the strand distributor,

a carriage mounted for free displacement transverse to the reel with a strand when the strand is distributed on the reel,

a light source mounted on the carriage and carried by the carriage on one side of the reel,

a photoelectric sensing element mounted on the carriage directly opposite the light source and on the side of the reel opposite to the light source so that light from the light source passes between the strand and its adjacent convolution to the photoelectric sensing element, the amount of light reaching the photoelectric sensing element from the light source being a function of the distance between the strand and its adjacent convolution,

means responsive to the amount of light reaching the photoelectric sensing device for controlling the rate at which the strand distributor traverses the reel,

means actuated upon the carriage reaching either flange of the reel for lifting the carriage,

means actuated upon the strand reaching either flange of the reel for stopping the displacement of the distributor,

means actuated upon the strand reaching either flange of the reel for detecting and counting each magnetized portion of the reel flange as the magnetized portions are rotated past a predetermined point,

means responsive to the detecting and counting means being actuated after a predetermined number of magnetized portions have passed the predetermined point for actuating the displacing means to displace the distributor across the reel, and
 means responsive to the detecting and counting means and actuated after a predetermined number of magnetized portions have passed the predetermined point for lowering the photoelectric sensing means.
